Primary Examiner — Elizabeth J Oswecki(57) **CLAIM**

The ornamental design for an insole, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a bottom plan view of an insole, showing my new design.

The dash-dot-dash broken line illustrates a boundary that forms no part of the claimed design. The remaining broken lines depict portions of the insole that form no part of the claimed design.

The color of the speckles forms part of the claimed design. The surface area within the claimed portions of the insole, which is illustrated on a white sheet of paper, forms part of the claimed design and the particular color of that surface area forms no part of the claimed design.
